UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 11,988, dated October 26, 1880.

Application filed July 31, 1880. Term of patent 34 years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics; and it consists in the novel grouping and configuration of figures, hereinafter more fully described.

The accompanying photograph illustrates a face view of wall-paper having my new design.

15 Two parallel stripes, A and B, ornamented with a series of dots or beads, serve to inclose the design on two sides, as it is shown in the photograph. A vine, C, forming a series of S-shaped connected curves, forms the body of 20 the design. From the vine C grow branches *a a a*, &c., each ending in three oblong leaves. Flowers *b b b*, of circular form, and each appearing to open out from between two leaves, *c c*, also grow from the vine C in such manner

that two of these flowers come within one half 25 and but one within the other half of every S-shaped curve of the vine. The vine and its flowers and leaves, as arranged, cover nearly the whole background. The effect produced is that of a curving vine richly ornamented 30 with leaves and flowers of particular shapes, and running between parallel stripes.

I claim—

1. The design for wall-paper, consisting of the vine C, with its leaves *a* and flowers *b*, 35 substantially as shown.
2. The design for wall-paper, consisting of the flower-like figure *b c*, substantially as shown.
3. The design for wall-paper, consisting of 40 the vine C, with its leaves *a a a* and flowers *b*, and the stripes A and B, substantially as shown.

EDUARD LEISSNER.
